US0D1020871S

(12) **United States Design Patent** (10) **Patent No.:** **US D1,020,871 S**
(45) **Date of Patent:** **** Apr. 2, 2024**

(54) **PRINTER FOR ELECTRONIC COMPUTERS**

(71) Applicant: **Roland DG Corporation**, Hamamatsu (JP)

(72) Inventor: **Osamu Takenaka**, Hamamatsu (JP)

(73) Assignee: **ROLAND DG CORPORATION**, Shizuoka (JP)

(**) Term: **15 Years**

(21) Appl. No.: **29/767,193**

(22) Filed: **Jan. 21, 2021**

(30) **Foreign Application Priority Data**

Sep. 18, 2020 (JP) 2020-020038

(51) **LOC (14) Cl.** **18-02**

(52) **U.S. Cl.** ..... **USPC** **D18/53**

(58) **Field of Classification Search**

USPC D18/40, 43, 46, 47, 48, 50, 53, 54, 55, D18/56; D15/122, 135, 138; D14/307, D14/314, 432; D8/354, 363

(57) **CLAIM**

The ornamental design for a printer for electronic computers, as shown and described.

DESCRIPTION

FIG. 1 is a front view of a printer for electronic computers showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front top perspective view thereof;

FIG. 8 is a rear bottom perspective view thereof;

FIG. 9 is a front bottom perspective view thereof; and,

FIG. 10 is a rear top perspective view thereof.

The broken lines in the drawing views are included to show portions of the printer for electronic computers that form no part of the claimed design.

1 Claim, 8 Drawing Sheets
